UNITED STATES PATENT OFFICE.

ALBERT L. LAMBERT, OF NARBERTH, PENNSYLVANIA, ASSIGNOR TO AMERICAN MOTOR BODY COMPANY, OF PHILADELPHIA, PENNSYLVANIA, A CORPORATION OF DELAWARE.

CAR SEAT.

1,411,791.

Specification of Letters Patent.

Patented Apr. 4, 1922.

Application filed March 18, 1921. Serial No. 453,458.

To all whom it may concern:

Be it known that I, ALBERT L. LAMBERT, a citizen of the United States, residing at Narberth, in the county of Montgomery and State of Pennsylvania, have invented certain new and useful Improvements in Car Seats, of which the following is a specification.

My invention relates to railway car seats of the reversible-back type and particularly to seats provided with mechanism whereby upon the shifting of the back from one side of the seat to the other the seat portion is moved in a reverse direction and tilted upward slightly so as to provide a comfortable seating arrangement for the occupant.

One of the objects of my invention is to provide a mechanism for reversing the seat as above described, the mechanism being located beneath the seat, in exceedingly compact form. A further object of this invention is to provide a novel type of rocker operating mechanism which results in various advantages which will be pointed out hereinafter.

A further object of my invention is to provide means whereby the force applied at one end of the back to effect the reversal of the back and cushion is positively transferred to the opposite sides of the back and cushion to effect identical movement of both sides of the back and cushion simultaneously.

Other objects will be in part obvious and in part pointed out hereinafter.

In the accompanying drawings wherein is illustrated one possible embodiment of my invention, Fig. 1 is a vertical section of a seat embodying my invention taken on line 1-1 of Fig. 3, showing an end plate and the seat mechanism; Fig. 2 is a sectional view of the seat in intermediate position showing the wall plate and the seat mechanism; Fig. 3 is a section through the connection between the seat standard, the end plate and the rocker, and shows the mechanism for moving both sides of the back and seat-cushion in unison; Fig. 4 is an enlarged detail of certain parts of the seat-operating mechanism and Fig. 5 is a vertical section taken on line 5-5 of Fig. 4.

Similar reference characters designate similar parts throughout the several views of the drawings.

Referring to the drawings, reference char-

acter 1 represents an aisle pedestal for a seat, 2 a pair of cross members, 3 aisle and wall end plates, 4 a cushion carried by two rockers 5 on cross members 2, 6 a back having end standards 7 carrying at their lower ends rollers 8, 8 supported and guided in channel tracks 9, one on each end plate 3, and 10 represents a rocker rod. All the above elements of a reversible car seat are believed to be well known in the art. In addition thereto there are usually present means for automatically shifting the seat cushion when the back is reversed and also means for insuring identical and simultaneous movement of both ends of the back and of both ends of the seat in response to reversing pressure exerted upon one end of the back. It is to these two last mentioned means that my invention is particularly directed, and these means will now be particularly described.

In accordance with my invention, I provide a lazy-tongs 12, and fixedly pivot the same intermediate its ends, 13 and 14, respectively, centrally on the seat end 3 as at 15. At the lower end of back-supporting standard 7, and below the upper surface of seat cushion 4, I provide a pivot pin and pivot the end 13 of the lazy-tongs thereon. I pivot the other end 14 of the lazy-tongs to 85 rocker-rod 10 near one end thereof. As the back is moved from an extreme position towards intermediate position, the lazy-tongs will collapse progressively, and thereafter the lazy-tongs will become progressively extended until the other extreme position is reached. During this movement the lazy-tongs will also rotate about pivot point 15 and since the lazy-tongs are fastened to rocker-rod 10 as at 14, rocker-rod 10, rockers 5, and seat cushion 4, will be moved in a reverse direction to back 6, and the desired movement of the seat cushion is effected automatically upon the reciprocation of the back and simultaneously therewith. At the same time, on account of the collapsing feature of the lazy-tongs the vertical component between pivot point 13 and pivot point 14 is maintained substantially constant at all times and all the mechanism may be confined in an exceedingly small space and in compact form. With this mechanism considerable space under the seat is freed from seat mechanism and may be utilized for the storage of grips, packages or the like, or

for the installation of heating units well above the floor, and at the same time no part of the mechanism extends above the seat cushion, where it would be apt to catch into 5 a passenger's clothing or would occupy space desired for the accommodation of the occupant of the seat. It is believed that the employment of a lazy-tongs in the combination and for the purpose above described 10 is broadly new.

It is preferable, but not essential, to have the seat-mechanism at both ends of the seat identical, with a lazy-tongs mounted on each end, as above described. With such 15 a construction a positive power transmission device may readily be provided for effecting identical and simultaneous movement between both ends of the back and between both ends of the seat cushion in 20 response to seat reversing pressure applied to one end of the back. Such a device may comprise a shaft 16 extending longitudinally beneath the seat-cushion 4, with its end rotatably supported on the end plates 3, and 25 corresponding links 18 of the two lazy-tongs rigidly and centrally attached to shaft 16 adjacent its ends, respectively, so that shaft 16 will constitute the point of fixed pivot 15 for each lazy-tongs and the rotation 30 of one link 18, as occasioned by reversing movement of back 6, will cause rotation of shaft 16 and a rotation thereby of the link 18 of the other lazy-tongs in a manner identical and simultaneous with the 35 rotation of said first link. It is to be noted that another link 20 of each lazy-tongs also rotates about point 15, and these two links 20 may be rigidly connected to the ends, respectively of a sleeve 19, as by means of 40 annular rings 21 having flanges welded respectively to sleeve 19 and to links 20, sleeve 19 being mounted for free rotation about shaft 16, and adapted to maintain identical and simultaneous movement between links 45 20 during reversing movement of the seat.

Thus it is apparent that when one side of the back is moved to effect a reversal of the seat, as by the application of pressure to that side, the force so applied will be 50 transmitted through shaft 16 and sleeve 19 to the lazy-tongs at the opposite side of the seat, and through these lazy-tongs to the back-supporting standard 7 and also to the rocker rod 10, rockers 5, and the opposite side of 55 the seat cushion 4, all on that side of the seat which is opposite to the side to which the pressure is supplied, and both ends of the back and both ends of the seat cushion will be caused to move in unison.

60 It is to be understood that either shaft 16 or sleeve 19 may be used without the other, and also that many other modifications may be made in the construction above described without departing from the scope 65 of this invention.

What I claim is:

1. In a reversible car seat, the combination with a seat-cushion, a rocker supporting said seat-cushion, back-supporting standards movable past said seat-cushion, and an end plate, of a collapsible device pivotally supported on said end plate and pivotally connected to said back-supporting standard and to said rocker on opposite sides of its said point of pivotal support, 75 and adapted upon reciprocation of said back-supporting standard to effect reverse movement of said seat-cushion, and to maintain the vertical component between said standard and said rocker substantially constant at all times. 80

2. In a reversible car seat, the combination with a rocker supporting a seat-cushion, a back-supporting standard movable past said seat-cushion, and an end plate, of means for reciprocating said cushion in response to reciprocation of said back, said means comprising a lazy-tongs pivotally supported at one point on said end plate, pivotally connected at another point to said 90 standard and pivotally connected at a third point to said rocker.

3. In a reversible car seat, the combination with a rocker supporting a seat-cushion, a back-supporting standard movable past 95 said cushion, and an end plate, of means for moving said seat-cushion, in response to movement of said standard and in a reverse direction thereto, said means comprising a lazy-tongs pivotally supported intermediate its ends on said end plate and pivotally connected to said standard and to said rocker on opposite sides of said point of pivotal support. 100

4. In a reversible car seat, the combination with a rocker supporting a seat-cushion, a rocker rod, a back-supporting standard movable past said cushion, a pivot pin on said standard, below the upper surface of said cushion, and an end plate, of means for 105 moving said seat-cushion in response to reciprocation of said back and for maintaining the vertical component between said pivot pin and said rocker rod substantially constant at all times during said movements, 110 said means comprising a lazy-tongs pivotally supported on said end plate, and pivotally connected to said pivot pin and to said rocker rod. 115

5. In a car seat, the combination with 120 cross-rails, a support therefor, an end plate, a seat-cushion, a rocker supporting the same resting on said rails, a back-supporting standard movable in a substantially horizontal plane past said seat-cushion, and having 125 a pivot pin thereon disposed below the top surface of said cushion, of a chain of diagonally disposed levers pivoted together at their ends, one of said levers being fixedly pivoted intermediate its ends to said end 130

plate, said chain being pivotally connected to the pivot pin of said standard, and to said rocker shaft at opposite sides of said fixed pivot, whereby said chain becomes extended and collapsed according to predetermined movement of said back and the vertical component between said pivot pin and said rocker shaft is maintained substantially constant for all positions of said back and seat-cushion.

6. In a car seat, in combination, a movable back, two lazy-tongs, connected respectively to opposite sides of said back to permit movement thereof, and means including a rotatable shaft extending between said two lazy-tongs and attached to corresponding links thereof for effecting simultaneous and similar movement of both sides of said back.

7. In a car seat, in combination, a movable seat-cushion, mechanism at each side of said seat-cushion for moving the same, said mechanism including two lazy-tongs at opposite sides of said seat-cushion, and means including a rotatable shaft extending between said two lazy-tongs and attached to corresponding links thereof for effecting simultaneous and similar movement of both sides of said seat-cushion.

8. In a car seat, in combination, a movable back, a movable seat-cushion, mechanism including two lazy-tongs, one at each side of said seat, for moving said seat-cushion in response to movement of said back, and means including a rotatable shaft extending between said two lazy-tongs and attached to corresponding links thereof for effecting simultaneous and similar movement of both sides of said back and also simultaneous and similar movement of both sides of said seat-cushion.

9. In a car seat the combination with a moveable back and two lazy-tongs connected respectively to opposite sides of said back to permit movement thereof, of a rotatable shaft extending between said two lazy-tongs and attached to corresponding links thereof and a second rotatable member extending between said two lazy-tongs and attached to two other corresponding links thereof, whereby both ends of said back are caused to move in unison.

10. In a car seat the combination with a movable back, a movable seat-cushion and mechanism comprising two lazy-tongs, one at each side of said seat, for permitting movement of said back and for moving said seat-cushion in response to movement of said back, of a rotatable shaft extending longitudinally beneath the seat-cushion from one end of the seat to the other, a link of one of said lazy-tongs mounted on said shaft to rotate therewith and a corresponding link of the other lazy-tongs mounted on said shaft to rotate therewith, and in unison with said first link, whereby both ends of said back and both ends of said seat-cushion are caused to move in unison.

11. In a car seat the combination with a movable back, a movable seat-cushion, a pair of end plates one at each end of said seat, a seat mechanism for permitting movement of said back and for moving said seat-cushion in response to movement of said back, said mechanism comprising two lazy-tongs, one at each end of the seat, of a shaft extending longitudinally beneath the seat-cushion with its ends rotatably supported on said end plates, a link of one of said lazy-tongs mounted on said shaft for rotation therewith, a corresponding link of the other lazy tongs mounted on said shaft for rotation therewith and in unison with said first link, a sleeve mounted for rotation about said shaft and extending from one end of the seat to the other, a second link of said first mentioned lazy-tongs rotatably attached to said sleeve for rotation therewith and a second and corresponding link of said other lazy-tongs attached to said sleeve at the other end of said seat for rotation therewith and in unison with said second link of said first lazy-tongs, whereby the opposite ends of said back and the opposite ends of said seat are caused to move in unison.

This specification signed and witnessed this 11th day of March, 1921.
